UNITED STATES PATENT OFFICE.

HARRY W. BOLENS, OF PORT WASHINGTON, WISCONSIN.

DESIGN FOR A CHAIR-SPINDLE.

SPECIFICATION forming part of Design No. 33,313, dated October 2, 1900.

Application filed August 31, 1900. Serial No. 28,713. Term of patent 14 years.

To all whom it may concern:

Be it known that I, HARRY W. BOLENS, a citizen of the United States, residing at Port Washington, in the county of Ozaukee and State of Wisconsin, have invented and produced a new and original Design for a Chair-Spindle; and I do hereby declare the following to be a full, clear, and exact description of the same, reference being had to the accompanying drawings, forming a part thereof.

In the said drawings, Figure 1 is a side elevation looking from the point of view indicated by the dotted line 1 1 below Fig. 3. Fig. 2 is a like elevation taken at a right angle to the position shown in Fig. 1 and looking from the point of view indicated by the dotted line 2 2 at one side of Fig. 3. Fig. 3 is a horizontal sectional view taken on the dotted line 3 3 of Fig. 1 and looking downward, and Fig. 4 is a top or plan view of a chair-spindle embodying my new design.

My design relates to the new and original shape or configuration of the article.

The leading or essential feature consists in the unitary design for a chair-spindle made

the subject of illustration, comprising the shape of the body A, formed with two vertical parallel straight flat sides b b of same diameter throughout, said flattened sides interrupting an otherwise cylindrical body, which is, further, of a spirally-threaded external configuration, as shown at c c c, the continuity of said thread being interrupted by the said flattened sides b b, but the spiral line of said thread being continuous from top to bottom, together with the cylindrical head B of greater diameter than that of the said body A and the central vertical annular smooth walled bore C.

Having thus described my invention, what I claim as new, and desire to secure by Letters Patent, is—

The design for a chair-spindle, substantially as herein shown and described.

In testimony whereof I affix my signature in presence of two witnesses.

HARRY W. BOLENS.
